FLUID PRESSURE PUMP

Joseph B. Meyer, Kenosha, Wis.

Application February 17, 1945, Serial No. 578,442

1 Claim. (Cl. 103—246)

1

This invention relates to water lift pumps of the non-piston type primarily for use as a source of supply in domestic water systems.

Pumps of the character mentioned commonly include a pair of gravity-fed water-receiving chambers adapted to be submerged beneath the water level in a well and from which the water is elevated by application of fluid pressure to the chambers alternately.

As heretofore designed, such pumps are necessarily of a size to render them incapable of use in narrow wells of a few inches or less in diameter. The valve means commonly employed for controlling the application of fluid pressure to the chambers is usually operated or controlled by float-actuated connections extending from within the chambers and necessitating the use of a float in each chamber of a size to insure reliable operation. Each float must be capable of producing a buoyant force of sufficient magnitude not only to operate the valve means but also to sustain the weight of the operating connections and to overcome the frictional resistance of the packing glands through which the connections extend. In most instances it is the size of the floats required for reliable operation that imposes a limit beyond which the pump size cannot be reduced.

One object of the present invention is to provide a pump of the character mentioned capable of reliable use in wells narrower than was heretofore possible.

Other more specific objects and advantages will appear, expressed or implied, from the following description of an illustrative embodiment of the present invention.

In the accompanying drawings—

Figure 1 is a vertical sectional view of a fluid pressure pump constructed in accordance with the present invention, this section being taken substantially along the line 1—1 of Fig. 3.

Fig. 2 is a vertical sectional view taken substantially along the line 2—2 of Fig. 3.

Fig. 3 is a top plan view on a larger scale.

Fig. 4 is a horizontal sectional view taken substantially along the line 4—4 of Fig. 1.

Fig. 5 is a view similar to Fig. 1 with the parts rearranged to facilitate explanation.

The pump selected for illustration comprises a cylinder 10 adapted to be lowered into a narrow well 11 below the water level therein. A central vertical partition 12 divides the interior of the cylinder into separate water-receiving chambers 13 and 14 having separate intakes 15 and 16 at their lower ends through which the chambers are supplied by gravity from the well. Each intake

2

15 and 16 includes a suitable check valve 17 for preventing discharge therethrough.

Two discharge pipes 18 and 19 communicate with the bottoms of the chambers 13 and 14, respectively. In this instance both pipes 13 and 19 extend upwardly through the upper end head 20 of the cylinder 10 and communicate with a single discharge pipe 21 controlled by a conventional faucet 22. An outwardly opening check valve 23 in each pipe 18 and 19 determines the direction of flow therethrough.

Provision is made for supplying air or other elastic fluid under pressure to the upper ends of the chambers 13 and 14 alternately in a manner 15 to force water from each while the other is filling. In the pump shown this is accomplished by the use of a valve 24 arranged to receive pressure fluid from a suitable pressure tank 25 through a pipe 26 and operable to direct the fluid 20 to the chambers 13 and 14, alternately, through pipes 27 and 28, respectively, which communicate therewith through the end head 20. Although various forms of valves may be used, that 25 shown at 24 is a rotary four-way valve of a well known type equipped with the usual discharge port not shown.

In this instance the valve 24 is actuated and controlled by two fluid actuated pistons 29 and 30 operatively engaged with the opposite ends of 30 a rocker arm 31 carried by the valve 24 for actuating the latter. The pistons 29 and 30 are closely fitted for vertical reciprocation in cylinders 32 and 33, respectively, each of which is supported by and communicates with a pipe 34 or 35 that extends vertically through one of the chambers 13 or 14 to a point adjacent the bottom thereof. The pipes 34 and 35 function to transmit pressure from the chambers 13 and 14, respectively, to the cylinders 32 and 33 to thereby 40 actuate the pistons 29 and 30, alternately, and thereby oscillate the valve 24 from one position to the other.

Admission of fluid pressure to the pipes 34 and 35 is rendered responsive to the water level in the chambers 13 and 14. For this purpose each pipe is controlled by a float controlled valve 36 or 37 coacting with the lower end thereof. Each valve 36 or 37 is shown arranged beneath one of the pipes 34 and 35 and supported by a float 38 or 39 through a suitable stirrup 40 or 41 extending loosely through and guided by a disk 42 or 43 carried by one of the pipes. The arrangement is such that with either of the chambers 13 or 14 filled with water the float controlled valve 36 or 50 55 37 in that chamber is retained in elevated posi-

tion to close the lower end of the pipe 34 or 35 in that chamber; but when the water level in that chamber falls to a predetermined point, the valve in that chamber opens and exposes its associated piston 29 or 30 to the pressure in that chamber, whereupon the valve 24 is actuated.

From the foregoing it will be noted that the valve 24 is actuated by fluid pressure derived from the tank 25, and that the only function of the floats 38 and 39 is to control the relatively small and light weight valves 36 and 37. It will also be noted that, as a result of this arrangement, very narrow floats will function satisfactorily, and that the chambers 13 and 14 may also be of very narrow form.

Each of the pipes 34 and 35 is preferably carried by a plug 44 removably fixed in the end head 20 of the cylinder 10, the plugs 44 occupying openings of a size to permit withdrawal of the pipes 34 and 35 and the parts carried thereby in order to afford ready access thereto for inspection, replacement, or repair.

Fig. 5 illustrates the position of the several parts immediately after the valve 24 has been shifted to direct fluid pressure from the pressure tank 25 through the pipe 27 to the top of the water filled chamber 13. With the faucet 22 closed however there is no discharge of water from chamber 13 through the pipe 18. With the valve 24 thus shifted the air or elastic fluid in the top of the other chamber 14 is free to escape through the pipe 28 so that water is free to flow by gravity into the chamber 14 from the surrounding well until the chamber 14 is filled. The float controlled valve 37 is shown in open position; but it eventually closes as the water level in the chamber 14 rises.

When the faucet 22 is opened, the fluid pressure in the top of the chamber 13 forces water therefrom through the pipes 18 and 21 to and through the faucet until the water level in the chamber 13 lowers to a point where the float controlled valve 36 opens, whereupon the pressure in the chamber 13, transmitted through the pipe 34, acts upon the piston 24 and thereby shifts the valve 24 to direct fluid pressure through

pipe 28 to the top of the other chamber 14 and to open the top of chamber 13 to exhaust through the pipe 27. When this occurs, water at once discharges from the then filled chamber 14 through the pipes 19 and 21 to and through the faucet 22, and the chamber 13 again fills with water supplied by gravity from the well. Thereafter, the water continues to discharge through the pipe 19 until the faucet 22 is closed or until the float controlled valve 37 is reopened by the falling water level in the chamber 14, whereupon the valve 24 is shifted by the piston 30 into the position first described to again supply fluid pressure to the chamber 13 and to begin anew the cycle of operation just described.

The two chambers 13 and 14 thus function alternately to maintain a substantially continuous discharge of water through the faucet 22 until the faucet is closed, and to automatically renew that discharge whenever the faucet is reopened.

Various changes may be made in the embodiment of the invention hereinabove specifically described without departing from or sacrificing the advantages of the invention as defined in the appended claim.

I claim:

In a pump of the character described the combination of a narrow elongated container divided to form two separate gravity filled chambers, discharge means for said chambers extending upwardly through said container, valve means operable to admit fluid pressure to said chambers alternatively, a removable closure member for the top of each chamber, a fluid pressure conductor extending into each of said chambers and supported by said closure member thereof, a float controlled valve carried by the lower end of each of said conductors, and means actuated through said conductors for actuating said first named valve means, each of said conductors and associated float controlled valve being removable, as a unit, from a chamber upon removal of its supporting closure member.

JOSEPH B. MEYER.
